UNITED STATES PATENT OFFICE.

WILLIAM C. MORRILL, OF NEW YORK, N. Y.

DESIGN FOR A CONTAINER FOR SOAP-DISPENSERS.

45,675.

Specification for Design.

Patented Apr. 28, 1914.

Application filed February 10, 1914. Serial No. 817,925. Term of patent 14 years.

To all whom it may concern:

Be it known that I, WILLIAM C. MORRILL, a citizen of the United States, residing at the city of New York, borough of Manhattan, county and State of New York, have invented a new, original, and ornamental Design for a Container for Soap-Dispensers, of which the following is a specification, reference being had to the accompanying drawing, forming a part thereof.

Figure 1 is an elevation of the container

illustrating my new design. Fig. 2 is a horizontal cross section thereof on the line $x-x$ of Fig. 1.

I claim—

The ornamental design for a container for soap dispensers, as shown.

WILLIAM C. MORRILL.
